UNITED STATES PATENT OFFICE.

CHARLES R. MOSS, OF RICHMOND, VIRGINIA, ASSIGNOR TO CHARLES R. MOSS, EDWARD M. HALL, AND CHARLES W. MOSS, DOING BUSINESS UNDER THE FIRM-NAME OF CRYSTAL STONE-YEAST COMPANY, OF RICHMOND, VIRGINIA.

SCRUBBING DEVICE.

1,192,093.

Specification of Letters Patent. Patented July 25, 1916.

Application filed December 18, 1915. Serial No. 67,628.

To all whom it may concern:

Be it known that I, CHARLES R. Moss, a citizen of the United States, residing at Richmond, in the county of Henrico and State of Virginia, have invented certain new and useful Improvements in Scrubbing Devices, of which the following is a specification, reference being had to the accompanying drawings.

10 This invention relates to certain improvements in scrubbing devices and has relation more particularly to a device of this general character of a fountain type and it is an object of the invention to provide a novel and improved device of this general character wherein is employed a liquid container wherein the contents thereof are caused to be discharged from the container upon the admittance of air within the container through 20 the outlet thereof.

Furthermore it is an object of the invention to provide a novel and improved device of this general character including a liquid container detachably supported in applied 25 position whereby the same may be readily applied to or removed from operative position.

The invention also has for an object to provide a device of this general character 30 including scrubbing elements detachably and adjustably applied in operative position whereby my improved device may be employed with convenience and facility in corners or the like.

35 It is also an object of my invention to provide a novel and improved device of this general character including an elongated body provided with longitudinally spaced means whereby scrubbing elements, such as brushes, may be detachably and adjustably 40 engaged with the body and whereby a liquid may be discharged at a point between the scrubbing elements when applied to the body and whereby said liquid may be deflected directly upon certain of the scrubbing elements when the device is being employed in connection with surfaces angular to the horizontal.

The invention consists in the details of 45 construction and in the combination and arrangement of the several parts of my improved scrubbing device whereby certain important advantages are attained and the de-

vice is rendered simpler, less expensive and otherwise more convenient and advantageous 55 for use, all as will be hereinafter more fully set forth.

The novel features of the invention will be carefully defined in the appended claims.

In order that my invention may be the 60 better understood, I will now proceed to describe the same with reference to the accompanying drawings, wherein—

Figure 1 is a view in perspective of a scrubbing device constructed in accordance 65 with an embodiment of my invention; Fig. 2 is a longitudinal vertical sectional view taken through my device as herein embodied and at one side of its transverse center; Fig. 3 is a view in bottom plan of my improved 70 device showing a modified application of the scrubbing elements; and Fig. 4 is a sectional view taken substantially on the line 4—4 of Fig. 1.

As disclosed in the accompanying drawings, 1 denotes a body or plate of predetermined configuration but herein disclosed as rectangular in plan and having its opposite ends provided with the transversely disposed heads or blocks 2 depending therefrom, 80 while the longitudinal margins of the body or plate 1 are provided with the depending plates 3 whereby a compartment or chamber A is afforded to receive the container C. As herein disclosed, the under faces of the 85 heads or blocks 2 are provided with guide ways 4 produced in any desired manner and with which are adapted to be slidably engaged the heads 5 of the brushes B, although it will be understood that any other type of 90 scrubbing elements may be employed which would operate with convenience and facility.

In practice I find it of advantage to have the width of the device substantially equal to the length of the brush 5 and as illustrated in Figs. 1, 2 and 4, I show a single brush arranged at each end of my improved scrubbing device and it will be readily understood that when it is desired to operate in a corner or like place, a brush can be readily adjusted transversely of the device to permit a convenient entry within the corner or corresponding place. In the event that it should be desired to employ my device in connection with an increased area, it will be 100 perceived that two brushes B in longitudinal

alinement can be employed at the opposite ends of my device as is particularly illustrated in Fig. 3.

As herein disclosed, the container C has its inner wall 6 flat and adapted to contact with the inner face of the body or plate 1 intermediate the heads or blocks 2, said inner wall 6 adjacent its opposite ends and at opposite sides of its transverse center is provided with the openings 7 defined by the upstanding bosses 8 adapted to be received within the pockets or recesses 9 formed in the under face of the body or plate 1, and said bosses 8 are adapted to have engaged therewith the suitable retaining members, one of which as at 10 being disclosed as a nipple affording means whereby a connection may be had with a hose or other flexible tubing for a purpose to be hereinafter set forth, while the second means is shown as a headed bolt 11. It is to be observed that the nipple 10 is provided with an annular flange 12 which contacts with the outer face of the body or plate 1 as also does the head 14 of the bolt 11, whereby the container C is effectively clamped in applied position, yet can be removed with convenience and facility when the requirements of practice so require. As herein embodied, the outer or free end of the nipple 10 is normally closed by the screw cap 15 and I prefer to employ in connection with the cap 15 the gasket or compressible disk 16 whereby it will be assured that passage of air through the nipple 10 is prevented when the cap 15 is in applied position.

The bottom or outer wall 17 of the container C is gradually inclined longitudinally from end to end and adjacent its lower end the wall 17 is provided with the transversely disposed series of openings or perforations 18 through which the liquid within the container C is adapted to be discharged upon the reciprocation of the device incident to the scrubbing operation.

The liquid is adapted to be placed within the container C through the filling vent 19 normally closed by the cap 20, said vent 19 being positioned in close proximity to the upper end of the wall 17, whereby it will be perceived that it will be impossible to completely fill the container C with liquid when said liquid is inserted through the vent or opening 19. With the liquid within the container C in a quiescent state it will be readily understood that there will be no discharge through the openings 18 but that upon agitation of the liquid during the reciprocations of the device in operation, the liquid will be moved sufficiently to permit air entering within the container C through the openings 18 with the result that a certain amount of liquid will be caused to discharge intermittently through the openings 18.

22 denotes the hand grasp or operating member of conventional construction suitably secured to the outer face of the body or plate 1 and disposed longitudinally thereof and arranged at the transverse center 70 of such body or plate 1. However, I do not wish to be understood as limiting myself in any way as to the manner in which my device may be operated, as it will be self-evident that a handle may be suitably connected to the bail 23 for properly reciprocating my scrubbing device as well as through arrangements which may suggest themselves in practice.

When it is desired to use my improved device for flushing a surface, it will be readily perceived that the nipple 10 may be connected with a suitable source of water supply and that the water delivered within the container C will be discharged through the openings 18 upon the surface to be flushed. By this it will be seen that my improved device may be employed for two important operations.

My improved scrubbing device is especially adapted for use in connection with the walls of buildings or other vertically disposed surfaces. When it is desired to have the liquid flow out of the container C, the device is worked with the openings 18 95 disposed downwardly. When sufficient liquid has been discharged it is only necessary to reverse the brush and continue the scrubbing operation. In actual practice it has been clearly established that the shape 100 of the container C and more particularly the slope of the bottom 17, is of essential import especially when working at a high elevation. I also find it of advantage to have the lower end of the bottom wall 17 105 provided with the transversely disposed extension 21 bridging the space between the adjacent end wall of the container C and the adjacent guide 5 whereby the liquid discharged through the openings 18 will be 110 deflected upon the adjacent brushes and will be deflected upon the surface being cleansed. Should a brush become unduly worn, the same may be readily and conveniently replaced without the necessity of the operator 115 returning to the ground or other base of operation as the brushes B are of such size as to be conveniently carried in a pocket.

From the foregoing description, it is thought to be obvious that a scrubbing device constructed in accordance with my invention is of an extremely simple and comparatively inexpensive nature and is particularly well adapted for use by reason of the convenience and facility with which it 125 may be assembled, and it will also be obvious that my invention is susceptible of some change and modification without material departure from the principles and spirit thereof and for this reason I do not wish to 130

be understood as limiting myself to the precise arrangement and formation of the several parts herein shown in carrying out my invention in practice.

5 I claim:

1. A device of the character described comprising an elongated body, brushes carried by the under surface of the body and disposed transversely thereof, said brushes being spaced apart longitudinally of the body, a container carried by the under surface of the body intermediate the brushes, the bottom of the container adjacent one end being provided with a transverse row of restricted openings, the bottom of the container being inclined outwardly relative to the body toward the end of the bottom provided with the openings, the upper end portion of the bottom being provided with a filling opening at a point inwardly of and spaced from said upper end, and removable means for sealing the filling opening.

2. A device of the character described comprising an elongated body, brushes carried by the under surface of the body and disposed transversely thereof, said brushes being spaced apart longitudinally of the body, a container carried by the under sur-

face of the body intermediate the brushes, the bottom of the container adjacent one end 30 being provided with a transverse row of restricted openings, the bottom of the container being inclined outwardly relative to the body toward the end of the bottom provided with the openings, the upper end portion 35 of the bottom being provided with a filling opening at a point inwardly of and spaced from said upper end, and removable means for sealing the filling opening, the end of the body provided with the openings 40 being provided with an extension disposed transversely thereof and inclined outwardly relative to the body and in continuity with the bottom of the container, the outer surface of the extension serving to carry the 45 liquid discharged through the restricted openings in the bottom of the container upon the adjacent brush when the device is being reciprocated in a vertical direction.

In testimony whereof I hereunto affix my 50 signature in the presence of two witnesses.

CHARLES R. MOSS.
